GALLEY MECHANISM FOR MONOTYPE MACHINES

Frank J. Lemieux, Central Falls, R. I.

Application September 13, 1932
Serial No. 632,963

8 Claims. (Cl. 199—95)

This invention relates to galley mechanism of the kind used in connection with monotype machines wherein the type is automatically cast, composed and assembled as delivered in measured lines to the galley support.

The primary object of this invention is to provide an automatic line tripping mechanism for the assembled type as it passes through the type channel whereby the measure of the line may 10 be lengthened or shortened as desired so that the line hook will be operated after a predetermined measure of type has been cast and projected forwardly in the line channel after which the type is released from the channel and automatically moved over the galley support.

A still further object of this invention is to provide an automatic line tripping mechanism which may be used for casting a series or plurality of type of the same character known in 20 the art as sorts.

A still further object of this invention is to eliminate the necessity of having to perforate a control ribbon to give matrix case position, and delivery of line. With the present invention it 25 is only necessary to perforate one character and then type will be delivered automatically the length of the line determined by the adjustable gauge on the pivoted lever embodying this invention which saves considerable time and 30 labor, due to the fact that it is only necessary to make one perforation in the control ribbon.

At the present it is necessary to perforate a control ribbon for each character in the line in order to deliver the line automatically i. e. if 35 there are sixty characters in the line it would be necessary to strike this character on an average of sixty times on the keyboard so that the characters could be delivered on to the galley automatically.

40 A still further object of this invention is to provide a device of the above mentioned character which may be attached to existing commercial monotype machines without requiring the use of tools other than a nut engaging wrench 45 and does not require the alteration of the monotype machine to accommodate the invention.

Other advantages and objects will become apparent during the course of the following description, forming a part of the specification, 50 taken with the accompanying drawings, wherein:

Figure 1 is a top elevational view of a monotype machine galley mechanism showing the embodiment of this invention as applied thereto;

55 Figure 2 is a top elevational view of a section

of the galley mechanism illustrating the manner in which the invention is applied to the tool supporting tray and the springs for normally holding the rocking lever in position;

Figure 3 is a top plan view of the cam wheel 60 fastened to the driving shaft of the conventional type for casting machines illustrating the position of the trip lever relative thereto and showing the manner in which an extension is secured to the trip lever adapted to be in the 65 path of a downwardly extending rod rigidly fastened to the rocking lever presented in the path of the type channel;

Figure 4 is a top plan view greatly enlarged 70 showing the rocking lever and the corresponding position thereof relative to the sorting tray;

Figure 5 is an inverted side elevational view 75 greatly enlarged showing the trip lever extension in the path of the rocking lever extension and the parts shown are disassembled from the type casting machine to better illustrate the construction thereof;

Figure 6 is an inverted side elevational view 80 of the rocking lever extension showing the same disassembled from the rocking lever and illustrating the manner in which the same may be fastened thereto in a rigid manner; and

Figure 7 is an edge elevational view showing 85 the rocking lever and the washers for holding the same in place upon the type channel block adjusting screw.

Attention is directed to the drawings, wherein like reference characters will be employed to designate like parts throughout the same.

The present invention is illustrated as being 90 applied to a monotype casting machine of the present day type and it is believed that it will be sufficient for present purposes to designate some of the elements included in said machine. The machine referred to comprises a type assembling or align channel 10 provided at the entrance with jaws and continuing outwardly from the machine between a vertically movable galley blade 12 and a horizontally movable line transerrer 13. The former is located at the entrance of the galley 14 having an adjustable galley wall 15. The adjustable wall 15 is connected at one end to the adjustable support 16 of the trip 17. Mounted for sliding movement 105 on the line transerrer is the type support 18 and traversing longitudinally of the line channel is the line carrier 19.

The machine also includes a type channel block 20 having an adjusting screw 21. 110

The mechanism for operating and controlling the movement of the line carrier, galley blade and line clasper in timed relation is connected to the driving shaft 23 through a single revolution clutch 24 under the control and operation of a trip lever 25. The trip lever is controlled by a signal in the record strip whereby the galley is set in operation and operates to discharge the assembled line of type into the galley.

10 The structure thus far described is embodied in the present day monotype machine as commercially used in print shops and the mode of operation is as follows:—

15 The type casting mechanism is governed by a perforated strip of paper which is known as signals that represent individual type which are cast by the casting block and automatically ejected from the casting block into the type channel 10 between the jaws 11. Separate signals are provided in the record strip which are known as justification signals and these signals operate suitable mechanism to actuate the trip lever 25 and which movement closes the clutch 24 during one revolution of the driving shaft 23. 20 The line hook 19 is moved by its actuating lever designated by the reference character 26 operated by the cam wheel 27. The line hook 19 is moved to a point back of the last type character of the line and by reason of the configuration of 25 the cam slot in the cam wheel 27, the line hook 19 is again moved outwardly to bring the line of type outwardly along the type channel 10, to a position opposite the galley 14 whereupon the galley blade 12 is automatically raised and the line transfer 13 shifts horizontally to move the assembled line of type onto the galley 14. The line hook 19 is then returned to its normal position as shown in Figure 1. At this point in the 30 operation the lever 25 is actuated by a suitable mechanism to open the clutch 24 whereupon the machine is in condition for another cycle of the desired operation.

35 The form of machine above described operates to form an assembled line of individual type which are of the same length and measure corresponding to the number and length of type represented by the record strip and no means provided for adjusting the measure of the type strip other than the size of the individual type 40 which is made larger or smaller in accordance with the desired measure of the line to be produced. It has been found when the machine is operating without an operating signal as when 45 it is desired to produce a number of individual types of the same character that it is necessary to hold the trip lever 25 so that the clutch 24 is disengaged whereupon the casting machine will operate to eject the several individual type characters at each operation or movement of the 50 line hook 19.

55 Various means have been employed for holding the trip lever 25 in a manner as above described to hold the clutch 24 disengaged for the purpose of producing sorts but this practice has been found objectionable due to the injury which can be caused to the operator should he not exercise due care and diligence. The methods heretofore used have included the inter-position 60 of a line of type between the frame of the machine and the trip lever 25 in such a manner as to hold the clutch 24 disengaged whereupon the casting machine will eject several type characters of the same form after which the operation 65 of the machine will be set into effect to again

move several more of the same type characters into alignment with the galley 14. In practicing this mode of operation, quite frequently the operator had his fingers caught between the line hook operating lever 26 and has very badly injured his hand through such an operation. It is the purpose of the present invention to provide an interchangeable device which may be employed for accomplishing the above objects and at the same time reduce hazards of injury to the operator.

70 The present invention comprises a pivoted angle bar 30 which may be pivotally secured to the type channel block adjusting screw 21 by removing the same and placing thereon a washer 31 having a vertical boss 32 adapted to fit an opening in one end of the angle bar 30. After the angle bar 30 has been positioned on the washer 31, a flat washer 33 is placed on top of the pivoted angle bar whereupon the adjusting screw 21 may be threaded into place on the type channel block 20. It is proposed to position the pivoted angle bar 30 so that the same overlies the line hook 19 as is clearly shown in 75 Figure 1. On the free end of the pivoted bar 30 there is provided a U-shaped guide 34 having the free ends flanged as at 35 so that they will lie flush with the pivoted angle bar in the direction of the extension 36 and may be fastened by 80 means of screws or rivets 37. Slidably mounted in the guide plate 34 is a squared rod 38 having on one end thereof a foot 39 adapted to project into the type channel 10 also clearly shown in Figures 1 and 2. It is to be understood that 85 the free end of the lever 30 may be provided with a projection extending into the line channel which would produce the same results as the foot portion 39 on the sliding rod 38. A coiled spring 40 has one of its ends connected to the pivoted angle bar 30 by being passed through 90 an opening 41 while the opposite end of the coiled spring 40 may be connected to the sorting tray 42 as at 43. It is to be understood 95 of course that the sorting tray 42 is supported above the mechanism as shown in Figure 1 and 100 held in place by a screw threaded rod, not shown, passing through the boss 44 and held in place by a nut also not shown.

105 The invention, further includes a bar as shown in Figure 6, designated by the reference character 45 having an offset portion 46 and a straight free end 47. The opposite end of the bar 45 is reduced and screw threaded as at 48 for receiving a washer 49 and a retaining nut 110 50. The reduced end 48 of the bar 45 is passed through an opening in the angle bar 30 and is held in place by the washer 49 and the nut 50 so that the offset bar 45 extends downwardly and out of the path of the line hook 19.

115 Attention is directed to Figure 5 wherein is shown the pivoted angle bar 30 having the extension bar 45 secured thereto by means of the nut 50 secured on the threaded reduced end 48 whereupon the laterally extending bar 45 will pass downwardly and the free end 47 is present 120 in the path of an extension bar 52 which is slightly curved as shown in Figure 5 and is provided at one end with a flat support 53 having an opening 54 for receiving the adjusting screw 125 55 of the trip lever 25.

130 As shown in Figure 3, the trip lever 25 is provided with an extension 52 which is slightly offset or curved so that as the angle lever 30 is operated by the line of type moving through 135 the type channel 10 the lower end 47 of the

extension rod 45 will engage the trip lever extension 52 and operate the clutch 24. It will be noted that the foot 39 is maintained at all times in the path of the type channel and by 5 operating a thumb screw 56 on the guide plate 34, the rod 38 may be adjusted to any desired measure of type line.

Having thus described the invention, what I claim is:—

- 10 1. The combination with a type casting, composing and setting up machine having a type channel-way, a galley support, a type channel block and a trip lever mechanism, of a means operable by the movements of the type in the 15 channel-way pivoted to the type channel block for controlling the trip lever whereby the trip lever may be controlled to operate the machine at predetermined intervals.
- 20 2. The combination with a galley mechanism having a sorting lever therefor, of a member pivotally associated with the galley mechanism and extending into the type channel thereof in the path of the type line and means associated therewith for tripping the starting member at predetermined intervals to produce a series of similar type characters.
- 25 3. The combination with a type casting, setting and composing machine having a galley mechanism, of a pivoted angle lever associated with the galley mechanism having the free end extending into the path of the type channel, adjustable means carried by the free end of the pivoted angle member for shortening or 30 lengthening the measure of the type line and means operable by the movement of the pivoted angle lever for controlling the starting and stopping of the galley mechanism.
- 35 4. The combination with a type casting, composing and setting machine having a galley mechanism, of a pivoted lever pivotally secured to the type channel block and adapted to overlie the line carrier so that the free end thereof will extend in approximation with the line channel, an adjustable finger carried by the free 40 end of the pivoted angle bar adapted to extend into the type channel-way to be engaged by the type, and means connecting the pivoted angle bar with the trip lever of the galley mechanism whereby the machine may be started at predetermined intervals according to the desired measure of type.
- 45 5. The combination with a type casting and composing machine having a galley mechanism, of a substantially flat angle bar pivotally secured to the type channel block of the galley mechanism whereby the free end of the pivoted angle bar will extend in approximation to the type channel, adjustable means on the free end 50 of the pivoted angle bar adapted to extend into the type channel-way, a laterally extending bar having one of its ends connected to the pivoted angle bar, said laterally extending bar being adapted to extend downwardly, an extension formed on the trip lever of the galley mechanism adapted to extend in the path of the laterally 55 extending bar secured to the pivoted angle bar whereby movements of the angle bar will effect movement of the trip lever extension to start the galley mechanism.
- 60 6. The combination with a type composing and casting machine having a galley mechanism, of a pivoted bar having an angle portion adapted to extend in approximation to the type channel-way of the galley mechanism, said angle bar having a pivotal connection to the type channel block of the galley mechanism and adapted to be inter-changeable thereon, a 65 downwardly extending offset bar having one of its ends secured to the angle portion of the pivoted bar, an extension secured to the galley mechanism starting trip lever adapted to be positioned in the path of the downwardly extending offset bar whereby movement of the pivoted angle bar will effect movement of the starting trip lever mechanism.
- 70 7. The combination with a monotype casting and composing machine having a galley mechanism and a starting mechanism therefor, of a lever pivotally secured to the type channel block of the galley mechanism, an angle portion formed on the pivoted lever, said angle portion being extended in the direction of the type channel-way, a slide bar guide secured to the outer end of the angle portion of the pivoted lever, a slide bar slidably mounted in the 75 slide bar guide, a thumb nut secured to the slide guide for adjusting the slide bar in any desired position, a foot formed on one end of the slide bar adapted to extend into the path of the type channel, a downwardly extending offset bar having one of its ends connected to the angle portion of the pivoted lever, and an extension bar secured to the trip lever of the starting mechanism adapted to lie in the path of the downwardly extending offset bar, whereby movement of the pivoted lever effected by the slide bar foot engaging the line of type will effect the starting of the galley mechanism.
- 80 8. The combination with a monotype casting and composing machine having a galley mechanism and a starting mechanism for the galley mechanism, of a lever pivotally secured to the channel block of the galley mechanism extending outwardly and parallel with the type channel, an angle portion formed on the pivoted lever, an adjustable slide bar transversely mounted on the pivoted lever at the end of the angle portion, said slide bar being adapted to lie in a position parallel to the type channel of the galley mechanism, a foot secured to one 85 end of the slide bar adapted to project into the path of the moving type in the channel-way, whereby movements of the type into engagement with the foot of the slide bar will effect the movement of the pivoted lever, spring 90 means for holding the pivoted lever in a set position and normally in the direction of the type channel-way, a downwardly extending bar having an offset portion secured to the angle portion of the lever, an extension bar secured removably to the trip lever of the galley starting mechanism, said extension bar being adapted to lie in the path of the movement of the downwardly extending offset bar whereby movement of the pivoted lever will effect the movement 95 of the galley starting mechanism trip lever to operate the clutch and to start the galley mechanism after a desired measure of type has been moved outwardly through the type channel.
- 100 9. The combination with a type casting and composing machine having a galley mechanism, of a pivoted bar having an angle portion adapted to extend in approximation to the type channel-way of the galley mechanism, said angle bar having a pivotal connection to the type channel block of the galley mechanism and adapted to be inter-changeable thereon, a downwardly extending offset bar having one of its ends secured to the angle portion of the pivoted bar, an extension secured to the galley mechanism starting trip lever adapted to be positioned in the path of the downwardly extending offset bar whereby movement of the pivoted angle bar will effect movement of the starting trip lever mechanism.
- 105 10. The combination with a monotype casting and composing machine having a galley mechanism and a starting mechanism therefor, of a lever pivotally secured to the type channel block of the galley mechanism, an angle portion formed on the pivoted lever, said angle portion being extended in the direction of the type channel-way, a slide bar guide secured to the outer end of the angle portion of the pivoted lever, a slide bar slidably mounted in the slide bar guide, a thumb nut secured to the slide guide for adjusting the slide bar in any desired position, a foot formed on one end of the slide bar adapted to extend into the path of the type channel, a downwardly extending offset bar having one of its ends connected to the angle portion of the pivoted lever, and an extension bar secured to the trip lever of the starting mechanism adapted to lie in the path of the downwardly extending offset bar, whereby movement of the pivoted lever effected by the slide bar foot engaging the line of type will effect the starting of the galley mechanism.
- 110 11. The combination with a monotype casting and composing machine having a galley mechanism and a starting mechanism for the galley mechanism, of a lever pivotally secured to the channel block of the galley mechanism extending outwardly and parallel with the type channel, an angle portion formed on the pivoted lever, an adjustable slide bar transversely mounted on the pivoted lever at the end of the angle portion, said slide bar being adapted to lie in a position parallel to the type channel of the galley mechanism, a foot secured to one end of the slide bar adapted to project into the path of the moving type in the channel-way, whereby movements of the type into engagement with the foot of the slide bar will effect the movement of the pivoted lever, spring 115 means for holding the pivoted lever in a set position and normally in the direction of the type channel-way, a downwardly extending bar having an offset portion secured to the angle portion of the lever, an extension bar secured removably to the trip lever of the galley starting mechanism, said extension bar being adapted to lie in the path of the movement of the downwardly extending offset bar whereby movement of the pivoted lever will effect the movement 120 of the galley starting mechanism trip lever to operate the clutch and to start the galley mechanism after a desired measure of type has been moved outwardly through the type channel.
- 125 12. The combination with a monotype casting and composing machine having a galley mechanism and a starting mechanism for the galley mechanism, of a lever pivotally secured to the channel block of the galley mechanism extending outwardly and parallel with the type channel, an angle portion formed on the pivoted lever, an adjustable slide bar transversely mounted on the pivoted lever at the end of the angle portion, said slide bar being adapted to lie in a position parallel to the type channel of the galley mechanism, a foot secured to one end of the slide bar adapted to project into the path of the moving type in the channel-way, whereby movements of the type into engagement with the foot of the slide bar will effect the movement of the pivoted lever, spring 130 means for holding the pivoted lever in a set position and normally in the direction of the type channel-way, a downwardly extending bar having an offset portion secured to the angle portion of the lever, an extension bar secured removably to the trip lever of the galley starting mechanism, said extension bar being adapted to lie in the path of the movement of the downwardly extending offset bar whereby movement of the pivoted lever will effect the movement 135 of the galley starting mechanism trip lever to operate the clutch and to start the galley mechanism after a desired measure of type has been moved outwardly through the type channel.
- 140 13. The combination with a monotype casting and composing machine having a galley mechanism and a starting mechanism for the galley mechanism, of a lever pivotally secured to the channel block of the galley mechanism extending outwardly and parallel with the type channel, an angle portion formed on the pivoted lever, an adjustable slide bar transversely mounted on the pivoted lever at the end of the angle portion, said slide bar being adapted to lie in a position parallel to the type channel of the galley mechanism, a foot secured to one end of the slide bar adapted to project into the path of the moving type in the channel-way, whereby movements of the type into engagement with the foot of the slide bar will effect the movement of the pivoted lever, spring 145 means for holding the pivoted lever in a set position and normally in the direction of the type channel-way, a downwardly extending bar having an offset portion secured to the angle portion of the lever, an extension bar secured removably to the trip lever of the galley starting mechanism, said extension bar being adapted to lie in the path of the movement of the downwardly extending offset bar whereby movement of the pivoted lever will effect the movement of the galley starting mechanism trip lever to operate the clutch and to start the galley mechanism after a desired measure of type has been moved outwardly through the type channel.

FRANK J. LEMIEUX. 145
